UNITED STATES PATENT OFFICE.

IDA MAY FULLER, OF NEW YORK, N. Y.

FIRE-ILLUSION APPARATUS.

1,254,790.

Specification of Letters Patent. Patented Jan. 29, 1918.

Application filed January 23, 1917. Serial No. 143,900.

To all whom it may concern:

Be it known that I, IDA MAY FULLER, a citizen of the United States, residing at New York, in the county of New York and State of New York, have invented certain new and useful Improvements in Fire-Illusion Apparatus, of which the following is a full, clear, and exact specification.

This invention relates to theater appliances and particularly to appliances for the simulation of fire by the billowing and illumination of a fabric in air currents.

The object of the invention is to effectively produce a realistic illusion of fire, in which the flames constantly change in position and character without ever appearing twice alike in the same place and form. A further object of the invention is to provide fire simulating apparatus which will economize the use of air blast, and not necessitate an installation either excessive in size or in the power consumed, even for extensive scenic effects.

The invention broadly resides in the combination of a colored fabric, representing the flame, with a normally invisible support or background, which controls the waving of the colored fabric, directs the air blast so as to produce a peculiar billowing of the fabric, and may also perform the function of scenery when the fire effect is not used.

The colored sheet is loosely hung so as to billow freely and easily; and the air currents passing between the sheet and the background need only be strong enough to gently billow the sheet in its suspended position, so that when properly lighted, it produces a realistic effect of an extensive fire.

The normally invisible background not only directs the air blast, but also is adapted to represent parts of scenery, such as buildings, draperies, window openings, etc., which are to be seemingly burned. The removal of the flame sheet and cutting off or change of the lighting can thus uncover a painted background which was previously invisible during the fire, so as to show an opening, or a distant landscape, or a charred wall, tree, etc. By this invention, much larger scenic fire effects can be produced without excessive apparatus, than with previously used fire illusion apparatus, and also this invention opens up a field for the use

of very large fire effects in conjunction with ordinary scenery which has not heretofore been available.

In the accompanying drawings,

Figure 1 is a front view in perspective of a stage scene provided with apparatus embodying this invention;

Fig. 2 is a sectional detail view;

Fig. 3 is a vertical sectional view;

Fig. 4 is a plan view;

Fig. 5 is a perspective view of a special application for a window, and

Fig. 6 is a vertical sectional view of the same.

In the drawings, 1 is a stage on which is scenery such as buildings 2, and trees 3. In order to simulate fire within the buildings and behind the trees, openings 4 are left for doors and windows in the buildings, and spaces 5 show between the trees. Through these spaces can be seen flame sheets or curtains 6, representing a fire within or behind the buildings and trees. These flame sheets can be vertical, or horizontal, or inclined.

These flame sheets 6 are made of light colored silk and are fastened to battens 7, at top and bottom, and are positioned over an open-work base 8, to which currents of air blow upwardly from fans 9 to billow or flutter the sheets. 10 is the normally invisible background or partition piece located just to the rear of and close to the flame sheet, and spaced from the bottom of the latter so that air passing through the netting 8 will irregularly billow and wave upwardly between the background and sheet, as well as in front, until it escapes at the top. This background can be of cloth, glass, etc., and marked and colored so as to represent openings, surfaces, etc., of any desired character. The front and rear air currents act in conjunction producing an irregular and continually varying billowing effect. This control of the air blast not only enables most realistic illusions to be produced, but also in directing and redirecting the currents laterally and vertically greatly economizes the air blast and enables extensive scenic effects such as distant forest fires, burning buildings, ships, etc., to be produced with apparatus neither excessive in size nor requiring excessive power.

Additional control of the air can be secured by the scenery in front of the

flame sheet, see Fig. 3, thus further guiding and economizing the blast.

The flame sheets, curtains, streamers or the like, 6, may be variously colored and shaded to coöperate with the lighting in producing the illusion of flames and smoke. Where it is desired to give the appearance of sparks in the fire, bright reflecting spots 21 will be fastened to the sheet to sparkle in 10 the rays of light. Sparks may also be simulated by introducing bright pieces of colored material into the front air blast, and it is apparent that the flame sheet of this invention may be combined in any desired 15 manner with other fire simulating appliances such as fluttering streamers, etc.

The illumination for the curtain may be furnished by lights placed in any desired manner with relation to the curtain. In 20 Figs. 1 to 4, the sheet is lighted by lamps 11 below, and lamps 12 at the sides, all of which lamps are located near the plane of the curtain so that the billows and ripples will be accentuated and produce areas of light and 25 shade which sweep across the curtain like flames of fire. Means may be provided whereby the coloring of the lights will be rapidly varied to indicate the changing colors in the flames. Additional lights may be 30 used to accentuate certain local effects, and as shown in Fig. 3, the rays of lamp 13 in the wings serve to illuminate the trees and buildings silhouetted against the conflagration behind them.

To indicate the spread of the fire the illumination of the sheets may be carried on in a progressive manner and the sheet itself may be bodily moved with the same effect to extend the burning over the scenery behind, 40 and to finally disappear entirely and uncover a background of the blackened and charred remains, represented preferably on the rear screen or partition 10.

The rear partition or background 10, if 45 desired to remain invisible after the fire, can be a dull black. It may be made to represent an ordinary window frame or door in connection with the burning of a curtain or drapery. When not specially illuminated 50 and billowed by the air, the sheet 6 appears simply as an ordinary curtain or drapery.

In Figs. 5 and 6 the flame sheet 16 is shown suspended to represent window curtains or draperies in front of the background 55 painted to represent the charred remains of a burned window. The sheet 16 while billowing and fluttering is illuminated and then lowered to uncover the background 17. This is done by raising counterweights 18 60 and dropping or raising the sheet. The effect produced is that of a progressing fire which leaves behind a blackened window casing. To heighten the illusion the top of the sheet 16 is extended beyond its points of 65 suspension and released in loose ends 20 of

irregular shape which flap in the air currents and give the appearance of lapping flames shooting from the window casing.

The method employed for the burning curtains, can be applied to the sails of a 70 ship, or a whole building or tent can be built of sheets which when set in motion will represent a conflagration seemingly consuming the whole structure. Sections of the curtain itself may be cut away to show parts 75 of the background behind.

The apparatus of this invention provides for a large variety of stage effects in which the simulated conflagration acts in a most realistic manner. In the fire produced by 80 the waving curtain, the flames constantly shift in location and in never ending succession, their height and character being controlled by the illumination and the air blast. The height and movement of the flames are 85 not limited by fixed lengths of streamers, or by the loose edge of a fabric simply flapping back and forth within a restricted compass. The invention while practically unlimited in its scope, is at the same time economical of air and power, because the air is not required to support as well as flutter the flame sheet, and the movement is more 90 irregular as compared with prior arrangements. 95

An additional use of this invention is to represent a river of fire, flowing lava, or other molten material either in pools or flowing, can be produced by causing the flame sheet to billow downward on a slightly inclined background by air currents from above, the background being painted to represent a volcano or mountain. By fastening the sheet loosely at all sides, while forcing the air through at one end and illuminating 105 from beneath or above, the mass would appear to bubble and boil. A prairie fire could be simulated in a similar manner with a flat sheet having holes through which bunches of grass would project, so that the sheet would 110 billow around the waving grass and seemingly consume it by blending with it. The red colored lights would tint the grass the proper color.

It will be understood, of course, that in 115 adjusting the apparatus to produce the desired effect, the operator will suitably adjust the speed of the fan motors, and the direction of the blast, in the manner best adapted to meet individual conditions. 120

The details of the apparatus may be changed to accommodate it to various scenes, and the invention is not confined to the specific embodiments shown herein, but is intended to cover such modifications thereof 125 as fall within the scope of the appended claims.

I claim:—

1. In fire illusion apparatus, the combination with a sheet supported to be billowed 130

by air currents, of an air guiding surface placed in proximity thereto so as to leave a compact space between said sheet and said surface, means for illuminating said sheet, and means for directing air currents between said sheet and said surface to billow said sheet in a manner simulating flames of fire.

2. In fire illusion apparatus, the combination with a suspended sheet arranged to be loose and full in all directions, of an air guiding surface placed in proximity thereto so as to leave a compact space between said sheet and said surface, means for illuminating said sheet, and means for directing air currents between said sheet and said surface to billow said sheet in a manner simulating flames of fire.

3. A stage apparatus comprising a sheet, curtain or the like, a normally invisible background behind said curtain representing a surface exposed to fire, means for forcing air between said partition and said curtain to billow it, means for illuminating said billowing sheet to produce an illusion of fire, said curtain being removable to expose said background and represent the after effect of fire.

4. In stage apparatus, the combination of

a loosely suspended sheet, means for directing air currents along said sheet to billow it in a manner imitating the movement of flames, means for illuminating said sheet to produce an illusion of fire, a background behind the sheet representing a burned surface corresponding to the flame area of said sheet, and means for removing said sheet to expose said background representing the charred remains seemingly caused by the sheet of flame.

5. In fire illusion apparatus, the combination with a sheet suspended to loosely billow, means for directing air currents along said sheet to billow it, means for illuminating said sheet to produce areas of light and shade which sweep across the sheet and simulate flames, and pieces of reflecting material scattered over said sheet and attached thereto in position to receive said illumination and intermittently glitter and represent flying sparks of fire.

In testimony whereof I affix my signature, in presence of two witnesses.

IDA MAY FULLER.
